UNITED STATES PATENT OFFICE.

WILLIAM HURSTER, OF RICHMOND HILL, NEW YORK, ASSIGNOR TO THE OVALITE COMPANY, INCORPORATED, A CORPORATION OF NEW YORK.

DESIGN FOR A LAMP BASE OR ARTICLE OF SIMILAR NATURE.

Application filed January 28, 1928. Serial No. 25,070. Term of patent 3½ years.

To all whom it may concern:

Be it known that I, WILLIAM HURSTER, a citizen of the United States of America, and a resident of Richmond Hill, county of Queens, and State of New York, have invented a new, original, and ornamental Design for a Lamp Base or Article of Similar Nature, to which the following is a specification, reference being had to the accompanying drawing, forming a part hereof.

In the drawing:

Figure 1 is a plan view of the lamp base or article of similar nature; and

I claim:

The ornamental design for a lamp base or article of similar nature substantially as shown.

WILLIAM HURSTER.
